COMBINED MULTIBAND ELECTRICAL
STRUCTURE AND SWITCHING MECH-
ANISMGale Garrison, Kearny, N. J., assignor to Radio
Corporation of America, New York, N. Y., a
corporation of Delaware

Application March 28, 1934, Serial No. 717,868

25 Claims. (Cl. 171—119)

This invention relates to a combination multi-band electrical structure and switching mechanism adapted for use in connection with electrical communication circuits.

5 It is the principal object of my invention to provide in one unitary structure, an arrangement of coupling units carrying circuit units or devices which may be severally used for a plurality of frequencies of alternating current, including 10 speech frequencies, carrier frequencies, radio frequencies and quasi-optical frequencies.

Another object of my invention is to provide a unitary structure as set forth in the principal object, which is so designed that the mechanism 15 may be quickly set on any one of the frequency bands within the range of the instrument.

A further object of my invention is to provide 20 a complete unitary structure made up of a plurality of quickly separable coupling units, and each of these units made up of supplemental or 25 circuit units arranged in cooperative position within the coupling units, whereby the proper circuit units may be brought into operation for the particular frequency band with which it is 30 to be associated.

A further object of my invention is to provide a single unitary structure composed of a plurality of coupling units, the parts of which are so constructed and arranged that they may be readily 35 assembled or dis-assembled.

A still further object of my invention is to provide 40 a structure of the class described which is relatively simple and easy and cheap to manufacture when the nature of the apparatus is taken 45 into consideration.

These and other objects will be understood by one skilled in this art, from a reading of the specification taken in connection with the annexed drawings, wherein:

40 Figure 1 is a side elevation of one form of my combination multi-band electrical structure and switching mechanism, as adapted to use for tuning radio receivers.

45 Figure 2 is a section on the line 2—2 of Figure 1.

Figure 3 is a section on the line 3—3 of Figure 1.

Figure 4 is a section on the line 4—4 of Figure 1.

Figure 5 is a horizontal sectional view on the axial center of Figure 1.

Figure 6 is a vertical central section through the front or control end of the device.

55 Figure 7 is a view on the line 7—7 of Figure 6,

but with the drive plate turned thirty degrees from the showing in Figure 6.

Figure 8 is a view on the line 8—8 of Figure 6.

Figure 9 is a view on the line 9—9 of Figure 6, both Figures 8 and 9 showing the manner of 5 fastening the drive shaft to the forward drive plate.

Figure 10 is a part-sectional view on the line 10—10 of Figure 5.

Figure 11 is an exploded sectional view on the 10 line 11—11 of Figure 10.

Figure 12 is a plan view of the switch contact side of one of the circuit units.

Figure 13 is a fragmentary perspective view looking at one end of Figure 12.

Figure 14 is a section on the line 14—14 of Figure 12.

Figure 15 is a bottom plan view of one of the frame switch units.

Figure 16 is a perspective view of one of the 20 switch contacts shown in Figure 15.

Figure 17 is an enlarged view of the switch-engaging parts on the line 17—17 of Figure 4.

Figure 18 is a vertical sectional view through the stop or positioning member shown on the 25 extreme right hand side of Figure 5.

Figure 19 shows a modified form of circuit unit that may be used in one or more of the coupling units.

Figure 20 is a view similar to Figure 19, but 30 of a still further modified form of circuit unit.

Figure 21 is a schematic diagram showing how my combination multi-band coil structure and switching mechanism may be utilized in a radio receiving system.

In the various views of the drawings, wherein like numbers refer to corresponding parts, 1 is a frame more or less skeleton in shape, having uprights or pedestals 2 and 3 at opposite ends thereof. Mounted on the pedestals 2 and 3, for 40 rotary movement, is a switching mechanism composed of a plurality of readily separable units which I prefer to refer to as coupling units, since these units contain other units which I shall hereinafter refer to as circuit units which carry parts 45 that make up circuits for circuits of the various coupling units, whereby the circuit units may be connected into a complete radio receiving system.

Preferably, for the purpose of ease and cheapness in manufacture, I prefer to make as many parts 50 of the coupling units, as well as the circuit units, in a similar manner. For example, referring particularly to Figures 1 and 5, each coupling unit

55 includes a casing 4 preferably of metal so as to act as a shield for all of the parts enclosed by it.

As illustrated, the casing 4 is provided with similar caps 5 at each end. The cap 5 has a plurality of indentations 6 which may be of any desired shape, a circular shape being preferred as indicated.

- 5 Positioned between the cap 5 on one unit and the cap 5 on the next adjacent unit, is a circular insulating disc 7 having perforations therein to fit around circular-shaped insulators 8, which fits into the indentations 6 on the two adjacent 10 caps 5. Thus it will be seen that the small insulating discs 8 act as driving or coupling means between the units. They also assist the insulator 7 in insulating one coupling unit from the other. While I have shown and described a 15 band 4 having two caps 5 at either end, it is to be understood that a cup-shaped member 4 may be used in which the bottom part takes the place of one of the caps 5, it being understood that the depressions 6 are made in the bottom to correspond 20 and cooperate with the similar depressions in the cap next adjacent the bottom of said cup-shaped casing 4. Since this is an obvious modification, it has not been shown in the drawings.
- At the right hand end of the structure, a driving plate 9, in the form of a circular disc, is used, the same being perforated to receive the insulators 8 as shown in Figures 6 and 7. Fastened to the driving disc 9 is a stub or drive shaft 10, the union between the two being made by depressing 25 the metal at 11 as shown in Figure 9, and providing a collar 12 securely fastened to the shaft 10, which collar fits in the depressed portion 11. The end of the shaft to the left of the collar 12 passes through a hole in the plate 9 and has an 30 upset head 13 as indicated in Figure 8. The opposite end of the coil structure is provided with a similar plate 9 and a stub shaft 14, connected thereto in the same manner as has been described with respect to the drive shaft 10. Likewise, a driving connection is made to the rear 35 plate 9 in a similar manner as for the forward plate, all as clearly shown in Figure 5.

The pedestals 2 and 3 have clearance notches to receive the stub shafts 10 and 14, which, however, have bearings in similar bearing plates 15. Referring to the drive end bearing plate 15, this is provided with an indentation 16 on its inner face, which indentation is adapted to pass over a boss 17 extruded or punched, or formed, 40 inwardly from the pedestal 2. The indentation 16 is provided with a tapped hole 18 to receive a screw 19 for holding the plate 15 in position. In addition, the metal of the plate 15 is provided with an extended boss 20 preferably made by extruding the metal of the plate so as to provide a 45 longer bearing surface for the shaft.

In assembling the structure, the two plates 15, similarly made as above described, are placed in position on their respective shafts and then the 50 structure, with the plates, is slid downwardly inside of the pedestals 2 and 3 so that the indentations 16 pass over the guiding means or bosses 17, and then the screws 19 are put into place, thereby rotatably mounting, through the medium 55 of the shaft 10, stub shaft 14 and control knob 21, the entire structure in the frame.

The casing 4 of each coupling unit is provided with a plurality of perforations or openings 22 through which project switch contacts or blades 70 generally referred to as 23. The switch contacts or blades 23 comprise parts of a circuit unit composed of a frame or support member having a body portion 24 and a stem 25 which may or may not be made integral with the body 75 portion 24. As shown in several of the views, for

example Figure 2, the body or base portion 24 is shaped to fit the inner periphery of the wall of the casing 4, being held thereto in any satisfactory manner as by screws 26 as shown in Figure 1, which screws are adapted to enter screw-threaded holes 27 in the base portion 24.

The switch contacts or blades 23 may be attached to the base portion 24 in any satisfactory manner. As shown in Figure 13, the blade has two tines 28 and 29 which pass through openings in the part 24, or they may be moulded therein. Preferably the tine 29 of each switch blade is formed so as to extend beyond the contour of the portion 24 for the purpose of acting as terminals for the electrical devices carried on the stem 25. These electrical devices may be differently constructed and have different electrical characteristics.

As shown in Figure 2, the stem 25 carries two coils, a primary 30 and a secondary 31, the terminals of the primary coil 30 being connected to contacts or switch blades *a* and *b*, while the ends of the secondary coil 31 are connected to the contacts or switch blades *c* and *d*, through their respective terminals 29. In Figure 3, the stem 25 carries a pair of coils 32 and 33 disposed in different relationship from the coils shown in Figure 2. The coil 32 is connected to corresponding contacts *a* and *b*, and the coil 33 to the contacts *c* and *d*, comprising a part of its circuit unit, similar to that described with respect to the coils shown in Figure 2. In Figure 4, the stem 25 carries a primary winding 34 and a secondary winding 35 wound together in one coil, and also a small condenser 36 which is connected 30 as shown in the upper right-hand part of the diagram of Figure 21. The windings 34 and 35 are each connected to the switch blades 23 of its particular circuit unit.

Since these circuit units carry windings of different turns and sizes of wire, and are differently arranged, as well as condensers, I have referred to them in the claims as impedances. In other words, the circuit units may carry resistances wound inductively or non-inductively, or windings in the shape of inductance coils, or condensers, so that all may be broadly included by the term impedances. Generally speaking, all the circuit units within the coupling unit A may follow the general order and arrangement of 40 those shown in Figure 2, although this is not obligatory. The same may be said with respect to the design of the circuit units in the coupling units B and C, although certain of these circuit units may take the forms shown in Figures 19 and 20, wherein primary and secondary coils are shown mounted on the stem 23, depending on the requirements of the wave band with which the circuit units are associated.

However, it is to be kept in mind that the impedances arranged on each circuit unit are such as to cooperate in the coupling units A, B and C to operate in a system covering the same wave band or range of frequencies. For example, in the diagram shown in Figure 21, the switching 60 mechanism, composed of the plurality of coupling units, is set to tune the input circuits of a hypothetical superheterodyne radio receiver to cover a certain band, for example the broadcast band from 200 to 550 meters; whereas, the sets of coils 70 to the right, going in an anti-clockwise direction around the dotted circles shown in Figure 21, are illustrative of an arrangement of impedances to cover the wave band from 750 to 2000 meters. The next set of impedances is for a wave band 75

having a length of approximately 12 meters; the next in order are the ones diametrically opposite the broadcast band impedances which may take in wave bands around 20 meters, while the next in succession may cover wave bands around 40 meters, and the next step 80 meters. Thus, in the arrangement of apparatus shown, six wave bands are covered with an arrangement of three coupling units A, B and C. It is to be understood, however, that the number of coupling units may be varied according to the receiving system used.

As shown diagrammatically in Figure 21, the coupling A carries circuit units for the antenna circuits connected to the tube 37. The coupling B carries circuit units for the transfer of energy from the output of tube 37 to the input of tube 38, while the coupling C carries circuit units associated with the elements of tube 38 which are illustrated as an oscillator. The receiving system need not be described in further detail as this may take various forms according to the wishes of the radio engineer or manufacturer of the receiving set.

However, to complete the circuit connections between the coupling units and the other parts of the system, I have provided switch contact members preferably carried by the same frame that supports the coupling units which have been described. These contacts are also in the form of units as shown by Figure 15, one unit for each coupling unit. The contact unit comprises an insulator 40 having holes 41 therein for attaching the insulator to the base or framework in any satisfactory manner as by rivets or screws 42. The insulator 40 preferably has a plurality of spaced openings 43 to increase the surface resistance between the several metallic contact members 44 mounted thereon. The members 44 are shown perspective in an enlarged view in Figure 16. Preferably the metal is of good conducting material such as spring copper or bronze and has upstanding lugs 45 with inwardly projecting fingers 46 on opposite sides of a pair of switch contacts 47, the free ends of which preferably have formations suitable for making good wiping contact with the switch blades 23 of the circuit units.

As will be seen from Figure 16, the metal is cut out at 48 between the projections 45 and the switch blades 47 so as to give the switch blades 47 as much flexibility as possible. As will be seen from Figures 15 and 2, the fingers 46 are bent over the narrow portions 49 of the insulator 40. Also, the insulator is provided with holes 50 through which the projecting ends 51 of the contact members extend, the ends 51 being provided with holes or notches 52 for making conductor connection thereto.

From what has been said, it will be seen that the contact members, including the contact blades 47, are securely locked in position on the insulator 40. The insulator 40 and its contact blades are mounted as shown in Figures 1 and 2 and other figures, so that as the coupling units are rotated by means of the shaft 10, the switch blades 23 of the circuit units, which blades extend through the casing members 4, are brought into successive engagement with the switch blades 47. These switch contacts are lettered in Figure 15 as a, b, c and d to correspond with the similar characters in Figure 21. In other words, the wires of the system are brought to the contacts a, b, c and d of the insulators 40 which are carried on the framework of the unitary structure as has been described.

It may be noted that the driving plate 8 at the operating end of the unit is provided with small openings or indentations 53 which are adapted to cooperate with a stop or positioning member in the form of a ball 54 carried in a spring 55 supported on the end of the frame, so that as the knob 21 is turned, the rotating coupling units will be positively positioned when the switch blades of the circuit unit, for a given wave band, are brought into contact with the stationary switch contacts carried by the various insulators 40. In the construction shown in Figure 18, the ball 54 is positioned in a hole in the spring 55, being permanently held therein by the bent-over part of the spring 55, so that when the coupling units are removed from the frame, the ball 54 is still held in position by the spring 55. Thus it will not fall out of position and become lost or cause trouble in re-assembling.

It may be mentioned that the casing 4 or shield screen may be brought to the potential of one end of one of the coils in a very easy and expeditious manner by providing one of the switch blades 23 with a lug 57 having an end 58 turned and projecting into one of the mounting holes 27, so that when this hole is tapped for the purpose of mounting the frame of the circuit unit to the shield 4, the tap will cut a thread in the portion 58 so that the mounting screw 26 will make contact with the shield screen 4 and a switch blade as has been described. Thus each shield screen may be brought to the lowest electrical potential of the devices included in the coupling unit, but the various coupling units may be at different potentials.

From the description, it will be observed that I have provided a plurality of radio frequency impedances arranged so as to tune a plurality of wave bands, all mounted in a single unitary structure composed of electrically shielded coupling units carrying within circuit units adapted to be connected into a system so that wave bands of various lengths may be brought into tuning arrangement.

It will be apparent that various changes may be made in the details entering into the arrangement of the mechanism without departing from the spirit of the invention or the scope of the appended claims.

For example, the shaft 10 may be attached directly to the end cap 5 and, if necessary, insulated therefrom; or the shaft 10 may be of insulating material.

What I claim is:

1. A combined multi-band electrical structure and switching mechanism for electrical circuits comprising a supporting frame and a plurality of coupling units carried by the frame, each unit including a shielding casing having a plurality of individual circuit units arranged around the inner periphery of its casing, said circuit units including impedances and contacts connected thereto, said contacts extending through the casing, contacts carried by the frame to be engaged by said contacts projecting from the casing units, means for mechanically operating one coupling unit by means of another, and means for moving the entire coupling structure with respect to the frame to cause different sets of said movable contacts to engage said contacts carried by the frame.

2. A combined multi-band electrical structure and switching mechanism as set forth in claim 1, further characterized in that the mechanical means for operating one coupling unit from the

- other comprises insulators positioned in adjacent casing parts of different coupling units.
3. A combined multi-band electrical structure and switching mechanism as set forth in claim 1, further characterized in that the shielding casings are of metal and have removable end caps, said caps having depressions therein carrying insulators which act as driving means from one casing unit to the other, as well as to assist in insulating the units one from the other.
4. A combined multi-band electrical structure and switching mechanism as set forth in claim 1, further characterized in that said contacts extending from each of the casings are in the form of switch blades, while the contacts on the frame are in the form of flexible blades to cooperate with said switch blades to secure good electrical contact.
5. A combined multi-band electrical structure and switching mechanism as set forth in claim 1, further characterized in that the coupling unit casings are drawn up from metal having one end integral with the side walls and closed by a metal cap having depressions, the bottom of one casing having depressions therein in alignment with the depressions in the casing cap of the next adjacent unit, and insulators fitting in said depressions to at least provide driving means from one casing unit to the next adjacent one.
6. A combined multi-band electrical structure and switching mechanism as set forth in claim 1, further characterized in that the coupling unit casings are of metal and circular in shape with the bottom of one casing being closely adjacent to the top of another, said top having a cover for closing the casing, the mechanical means for operating one unit from the other including insulator-fitting-cooperating parts in adjacent unit casings.
7. A combined multi-band electrical structure and switching mechanism as set forth in claim 1, further characterized in that the coupling units are insulated one from the other, and from the frame.
8. A combined multi-band electrical structure and switching mechanism as set forth in claim 1, further characterized in that end plates are drivingly but detachably positioned at opposite ends of said coupling units, said end plates having stub shafts for rotatably supporting the entire electrical structure on the frame.
9. A combined multi-band electrical structure and switching mechanism as set forth in claim 1, further characterized in that end plates are drivingly but detachably positioned at opposite ends of said coupling units, said end plates having stub shafts for rotatably supporting the entire electrical structure on the frame, said stub shafts being supported in detachable bearing plates carried by the frame.
10. A combined multi-band electrical structure and switching mechanism as set forth in claim 1, further characterized in that end plates are drivingly but detachably positioned at opposite ends of said coupling units, said end plates having stub shafts for rotatably supporting the entire electrical structure on the frame, said stub shafts being supported in bearing plates slidably mounted on portions of said frame, whereby the entire electrical structure may be quickly removed from the frame for the purposes described.
11. A combined multi-band electrical structure and switching mechanism as set forth in claim 1, further characterized in that end plates are drivingly but detachably positioned at opposite ends of said coupling units, said end plates having stub shafts for rotatably supporting the entire electrical structure on the frame, said stub shafts being supported in bearing plates slidably mounted on portions of said frame, said plates having notches and guiding means at opposite ends for said plates, said plates having formations to cooperate with said guiding means, and means for locking said plates in operative position on the frame.
12. A combined multi-band electrical structure and switching mechanism as set forth in claim 1, further characterized in that end plates are drivingly but detachably positioned at opposite ends of said coupling units, said end plates having stub shafts for rotatably supporting the entire electrical structure on the frame, said end plates being insulated from the coupling unit casings and the driving connections from the plates being through insulators similar to those used between the coupling units.
13. A combined multi-band electrical structure including a plurality of coupling units, each unit comprising a casing having separate impedance devices for responding to electrical impulses of a plurality of frequency bands and arranged around the inner periphery of its casing, contacts for said impedance device extending through said casing, other contacts separate from the casing to be engaged by the first-mentioned contacts, said units being so arranged and driven one through the other that the impedance devices for a given frequency band of the different units may be simultaneously brought into circuit through said contacts.
14. A combined multi-band electrical structure and switching mechanism as set forth in claim 13, further characterized in that in a plurality of the individual coupling units, the values of the impedances in the individual circuit units in one coupling unit are so adjusted in relation to the values of the impedances in the corresponding circuit units of the other coupling units that the coupling units will at all times respond to electrical impulses having the same difference in frequency when the values of external apparatus connected to said units remain identical.
15. A combined electrical structure as set forth in claim 13 further characterized in that the impedance devices for each coupling unit are shielded from the impedance devices of the other units and are also arranged to reduce parasitic effects of the said devices on the device connected into circuit.
16. A coupling unit for a structure herein described, comprising a shielding casing carrying projecting switch contacts, a plurality of impedances for responding to electrical impulses of a plurality of frequencies positioned within the casing and connected to said switch contacts, said casing being constructed for and provided with means for making a driving connection with the next adjacent unit when assembled in said structure and means for moving said unit to switch said impedances into said circuit.
17. A combined multi-band electrical structure as set forth in claim 1, further characterized in that the contacts carried by the frame comprise metallic members having a central portion embracing three sides of an insulating bar and having blades extending upwardly in close proximity to each other away from said bar, said metallic members having fingers disposed on opposite sides of said blades and bent over the fourth side

of said bar, and means on said metallic members for making wire connections thereto.

18. In a combined multi-band electrical structure as set forth in claim 1, further characterized in that connections are made to said circuit units through switch contact units each comprising an insulator fastened to the frame and having a plurality of spaced openings therein, metallic members having portions wrapped around that part of the insulator forming the sides of said openings, contact blades extending from said metallic members, and means for making wire connections to said metallic members.

19. In a combined multi-band electrical structure as set forth in claim 1, further characterized in that connections are made to said circuit units through switch contact units each comprising an insulator fastened to the frame and having a plurality of spaced openings therein, metallic members having portions wrapped around that part of the insulator forming the sides of said openings, contact blades extending from said metallic members, said insulator having holes therein along one edge and terminal strips extending from said metallic members through said holes to a point where wires may be connected thereto.

20. A circuit connection unit for an electrical structure of the class described comprising an insulator having means on one edge for mounting the insulator to a support, said insulator having spaced openings forming bars therebetween, metallic members having spaced parts wrapped around said bars, contact blades positioned between said spaced metallic parts and extending from said metallic members, said insulator having holes along the edge opposite the first-mentioned edge, and terminal portions of said metallic members extending through said holes and to a point where wire connections may be made thereto.

21. A combined multi-band electrical structure and switching mechanism as set forth in claim 1, further characterized in that end plates are drivingly but detachably positioned at opposite ends of said coupling units, said end plates having stub shafts for rotatably supporting the

entire electrical structure on the frame, and further characterized by having a spring supported by the frame and carrying a stop-positioning device, and means on at least one of said end plates for cooperating with said stop-positioning device.

22. A combined multi-band electrical structure and switching mechanism as set forth in claim 1, further characterized in that the end members of said structure have stub shafts for rotatably supporting the entire electrical structure on the frame, and further characterized by having a spring supported on the frame and carrying a stop-positioning device, and means on at least one of the end members for cooperating with said stop-positioning device.

23. A combined multi-band electrical structure and switching mechanism as set forth in claim 1, further characterized in that end plates are drivingly but detachably positioned at opposite ends of said coupling units, said end plates having stub shafts for rotatably supporting the entire electrical structure on the frame, and further characterized by having a spring carried by the frame and having an opening therein and one end bent over said opening, a ball positioned in said opening and retained therein by said bent-over end, and means on the end plate adjacent said spring for cooperating with said ball to positively position said structure as it is rotated.

24. A combined multi-band electrical structure including a frame and a plurality of coupling units rotatably carried by the frame, each unit comprising a shielding casing carrying a plurality of circuit units therein, said circuit units including impedances for responding to electrical impulses of different frequencies, said coupling units being held together by parts of said frame, the driving connections to and through the coupling units being made through insulators.

25. A combined multi-band electrical structure and switching mechanism as set forth in claim 1, further characterized in that shaft supporting means are attached to the opposite end coupling units.

GALE HARRISON.
